BICYCLE SEAT

George W. Worley, Bolivar, Tenn., assignor to Troxel
Manufacturing Company, Moscow, Tenn., a corpora-
tion of Ohio

Filed June 9, 1967, Ser. No. 7,419

Term of patent 14 years

(Cl. D90—16)

FIG. 1

FIG. 2

FIG. 3

FIG. 1 is a side elevational view of a bicycle seat showing my new design.

FIG. 2 is a top plan view thereof.

FIG. 3 is a sectional view thereof taken as on the line III—III of FIG. 2.

I claim:

The ornamental design for a bicycle seat, as shown.
